W. T. McCULLOUGH

CHIMNEY COWL

Filed Nov. 5, 1920

W. T. McCullough Inventor

By *J. Haughey* Attorney

UNITED STATES PATENT OFFICE.

WILLIAM T. McCULLOUGH, OF SALEM, MISSOURI.

CHIMNEY COWL.

Application filed November 5, 1920. Serial No. 421,977.

To all whom it may concern:

Be it known that I, WILLIAM T. McCULLOUGH, a citizen of the United States, residing at Salem, in the county of Dent and 5 State of Missouri, have invented certain new and useful Improvements in a Chimney Cowl; and I do hereby declare the following to be a full, clear, and exact description of the invention, such as will enable others 10 skilled in the art to which it appertains to make and use the same.

This invention relates to new and useful improvements in chimney cowls adapted to prevent downward pressure of wind and 15 atmosphere in the flue of a chimney and has for its primary object the provision of a rotatable elbow-shaped or angular element that is automatically positioned by the wind to prevent the wind from blowing down the 20 chimney and thereby providing free draft to said chimney at all times.

Another object of this invention is the provision of a chimney cowl of the above 25 stated character which will be simple, durable and efficient, and which may be manufactured and sold at a comparatively low cost.

With these and other objects in view, as 30 will become more apparent as the description proceeds, the invention consists in certain novel features of construction, combination and arrangement of parts as will be hereinafter more fully described and claimed.

35 For a complete understanding of my invention, reference is to be had to the following description and accompanying drawings, in which:

Figure 1 is a side elevation, illustrating 40 a chimney cowl constructed in accordance with my invention.

Figure 2 is a vertical sectional view of the same.

Figure 3 is a sectional view taken on the 45 line 3--3 of Figure 2.

Referring in detail to the drawings, the 50 numeral 1 indicates a chimney cowl adapted to be secured to a chimney 2 in any well known manner and includes a lower or anchoring section 3, an upper section 4 to which an elbow-shaped hood 5 is secured. The lower section 3 fits within the flue of the chimney 2 and is secured to said chimney in any desired manner and has depending downwardly over the same the section 4

and the latter is of a diameter greater than the diameter of the section 3. An annular member 6 is secured to the lower section 3 intermediate its ends and has formed on its periphery an annular track 7 to be engaged by grooved rollers 8 that are journaled to an annular member 9 soldered or otherwise rigidly secured to the lower end of the upper section 4. Annular member or ring 9 is an angle iron and has its horizontal flange 9' 60 spaced from the section 3 as seen in Figures 2 and 3.

An annular member or ring 10 is secured within the lower section 3 and has formed integrally with the same a bar or web 11 70 provided with a socket 12 adapted to receive a ball or sphere 13 formed upon a pivot rod 14. The ball or sphere is retained within the socket 12 by means of a removable plate 15 that is provided with an opening to permit the pivot rod 14 to extend through the same. The upper end of the pivot rod 14 is enlarged and secured to a bar 16 formed integrally with a ring or annular member 17 and the latter is secured within the upper 80 end of the upper section 4 so that said section is held against lateral movement in relation to the lower section 3, but will have free rotation in relation to the lower section. The rollers 8 traveling upon the track 7 also will prevent the upper section from wabbling in relation to the lower section.

The upper section 4 projects above the lower section 3 and has secured to its upper end the discharge or elbow-shaped element 5, the 85 exhaust end 17 of which is positioned or disposed laterally of the sections 3 and 4. The elbow-shaped section 5 is secured to the upper section 4 against rotation in relation thereto. A band 18 is secured to the section 90 4 and has secured thereto a vane 19 for positioning the exhaust end 17 of the discharge or elbow-shaped element 5 in an opposite direction from the direction in which the wind is blowing. The vane 19 will al-

ways maintain the device in such a position 95 that the wind will be prevented from blowing into the exhaust end 17 of the cowl, thus preventing downward pressure within the flue of the chimney.

100 While I have shown and described the preferred embodiment of my invention, it will be understood that minor changes in construction, combination and arrangement of parts may be made without departing 105

from the spirit and scope of the invention as claimed.

Having thus described my invention what I claim is:

5 A cowl having an anchoring section, a hood section into which said anchoring section extends and relatively to which it moves axially, an elbow section on the hood section, a ring within the hood section, a rod 10 depending from said ring substantially centrally of the hood section and into the anchoring section, said rod having an enlarged lower end, means in the anchoring section to journal said enlarged end, a removable plate 15 on said rod disposed over said enlarged end to secure said rod to the anchoring section, a track wall surrounding the anchoring section and spaced therefrom, an angle iron

rigid with and at the base of the hood section, one of the walls of said angle iron being disposed vertically, peripherally grooved rollers within the angle iron journaled on said last mentioned wall to engage said track at their grooves and the other wall of the angle iron extending inwardly and having an opening of greater cross sectional area than the anchoring section whereby it will be maintained spaced therefrom by the engagement of the rollers with the track. 20 25

In testimony whereof I affix my signature 30 in presence of two witnesses.

WILLIAM T. McCULLOUGH.
